[57] CLAIM

The ornamental design for a revolver barrel with integrated recoil reducer, as shown and described.

DESCRIPTION

FIG. 1 is a side elevational view of a revolver barrel with integrated recoil reducer, showing one embodiment of my new design.

FIG. 2 is a front elevational view thereof.

FIG. 3 is a top plan view thereof.

FIG. 4 is a rear elevational view thereof.

FIG. 5 is a bottom plan view, rotated one hundred eighty degrees relative to the view of FIG. 1.

FIG. 6 is a fragmentary, greatly enlarged, vertical sectional view through the foremost end of the embodiment of FIG. 1.

FIG. 7 is a front elevational view of another embodiment of my invention; and

FIG. 8 is a fragmentary, greatly enlarged, vertical sectional view through the foremost end of the embodiment of FIG. 7.

FIG. 1

FIG. 2

FIG. 3

FIG. 4

FIG. 5

FIG. 6

FIG. 7

FIG. 8
